DESIGN FOR A SOAP DISH

Harry I. Holton, Chicago, Ill.

Application June 24, 1943, Serial No. 110,516

Term of patent 14 years

To all whom it may concern:

Be it known that I, Harry I. Holton, a citizen of the United States, residing at Chicago, in the county of Cook and State of Illinois, have invented a new, original, and ornamental Design for a Soap Dish, of which the following is a specification, reference being had to the accompanying drawing, forming a part hereof.

In the drawing:

Fig. 1 is a top plan view of a soap dish showing my new design.

Fig. 2 is a side elevational view.

Fig. 3 is a longitudinal vertical sectional view taken approximately along the line 3—3 of Fig. 1.

Fig. 4 is an end elevational view of the soap dish shown in Fig. 1.

I claim:

The ornamental design for a soap dish, as shown.

HARRY I. HOLTON.
